[57] ABSTRACT

A package having a bottom receptacle portion and an openable cover fitting over the bottom portion and extending downwardly along the sidewalls of the bottom portion. One of the side walls of the cover has a cut-out portion providing a window therein. A card having a fold-line dividing the card into two panels is positioned between the cover and the bottom receptacle portion so that one panel extends into the receptacle portion of the box while the other extends downwardly between the sidewall of the receptacle portion and the windowed sidewall of the cover so that indicia appearing on the second panel is exposed through the window.

BACKGROUND OF THE INVENTION

1. Field of the Invention.

This invention relates to the field of packaging and more specifically to a unique combination of box and display, identification and reorder card.

2. Description of the Prior Art.

The problem of marking containers such as boxes with distributor's stock numbers and product identification numbers and making the numbers conveniently and readily available to the merchant for accurately reordering depleted or about to be depleted stock has long plagued manufacturers and distributors.

The problem is particularly prevalent where the product is removed from its shipping box by the retailer for display and sale. Typical of that type of product are those which are now commonly hung on pegs or hooks for display.

In the past, the distributor's stock number has generally been printed or stamped on the container in which a number of the items are sent to the retail outlet. When the items are removed from the shipping box for display by the retailer, the boxes usually are discarded. Thus, when the stock is sold out or nearly so, and the retailer desires to replenish his stock, the reorder or distributor's stock number and other necessary information may not be readily available to him. He often has to shuffle through his old invoices in search of the distributor's stock number, and then even if he finds the invoice, he may not be sure that it is actually the stock number of the item in question, particularly when there are several models or similar items in his line of goods.

SUMMARY OF THE INVENTION

My invention comprises a new combination of shipping box and sales display and reorder card which reduces the printing costs by eliminating the need for printing on the side of the shipping box. Further, my unique combination expedites the reordering of depleted stock without error, even by inexperienced personnel.

Basically, the invention comprises a shipping box having a receptacle portion and a cover portion fitting over the bottom in the well-known fashion. The cover has a cut-out portion in one side providing a window for a folded card which extends from inside the receptacle portion of the box over the edge of the side of the receptacle portion and downwardly across the window. That portion of the folded card which is exposed through the window carries desired indicia such as the distributor's stock number for reordering and other necessary information for use by the manufacturer, distributor and retailer.

Other objects, features and advantages of the invention will be apparent from the following detailed description taken in conjunction with the accompanying drawings showing two embodiments exemplifying the principles of the invention.

BRIEF DESCRIPTION OF THE DRAWINGS

FIG. 1 is an isometric view showing the box and card combination forming a package embodying the invention.

2

FIG. 2 is a sectional side elevation view showing the relationship of the elements of the closed package of FIG. 1.

FIG. 3 is a front elevation view of the package shown in FIGS. 1 and 2.

FIG. 4 is an isometric view showing a box and card combination forming a package exemplifying a second embodiment of the invention.

FIG. 5 is a sectional side elevation view showing the relationship of the elements of the closed package in FIG. 4.

FIG. 6 is a front elevation view of the package shown in FIGS. 4 and 5.

15 DESCRIPTION OF THE PREFERRED EMBODIMENTS

Referring now more particularly to the drawings wherein like numerals refer to like parts throughout the 20 several views, a first embodiment is shown in FIGS. 1-3 and a second embodiment is shown in FIGS. 4-6. The bottom receptacle portion 10 and cover 11 shown are identical in both embodiments and form a generally 25 rectangular box, other shapes of course, may be provided without departing from the spirit or scope of the invention.

The receptacle portion of the box has a rectangular bottom panel 10a and four upright sidewalls 10b, 10c, 10d, and 10e. The cover has a top panel 11a and four 30 depending sidewalls 11b, 11c, 11d, and 11e. The cover is slightly larger than the bottom so as to fit over the bottom in the well-known manner. The front sidewall 11b of the cover has a cut-out portion 12 providing a window therein.

Referring now specifically to FIGS. 1-3, a card 13 is provided having a fold-line 13a dividing the card into a display panel 13b and an information panel 13c.

As shown in FIGS. 1 and 2, the display panel 13b carries the items 14 to be displayed for sale, in this case 40 fishing lures. The second panel 13c carries on it the necessary information for expeditious handling of the goods by the manufacturer, distributor and retailer, such as the distributor's stock number stamp shown for 45 example at 15 in FIGS. 1 and 3.

The package is formed by placing the product carrying display panel 13b in the receptacle portion of the box and folding the information panel 13c downwardly 50 along fold-line 13a. The cover is then placed on to close the box and hold the information panel parallel to the adjacent sidewall 10b of the box while exposing the indicia on the information panel through the cut-out window 12 as best shown in FIGS. 2 and 3.

When the items are to be displayed for sale by the 55 retailer, the card 13 is removed from the box and the information panel 13c folded backwardly against the back side of the display panel 13b and the card is then hung on a peg in the usual manner. As the items are sold, the retailer may then refer to the back of the card to obtain the information for placing a reorder with the distributor.

In the second embodiment shown in FIGS. 4-6, the receptacle portion 10 and the cover 11 of the box are 60 identical to those shown in FIGS. 1-3. In this second embodiment however, the card 16 is somewhat different from the display card 13 of the first embodiment. While card 13 is preferably used where a number of

items are attached to the card for display by the retailer, card 16 may be used where the items to be sold are displayed individually such as by hanging one behind the other on a peg or hanger. In this case, the card 16 again is a two-panel card divided by a fold line 16a, however, the first panel 16b may carry instructions to the retailer such as, for example: "This card has the stock number of the merchandise in this box. Put it on the peg before hanging the merchandise for sale and use it for reordering."

The second panel 16c, like the panel 13c of card 13, carries the necessary information such as stock and reordering numbers shown at 17 in FIGS. 4 and 6 and other information for use by the manufacturer, distributor and retailer.

Here again, the package is formed by folding the card 16 along the fold-line 16a as shown in FIG. 4 and then placing the fold-line along the top edge of the sidewall 10b and placing the cover on as shown in FIGS. 5 and 6.

It is understood that the invention is not confined to the particular construction or arrangement of parts herein illustrated and described for exemplification, but embraces all such modified forms thereof as come within the scope of the following claims.

I claim:

1. A package comprising:

- A. an opaque shipping box for articles, said box having
  - 1. a bottom receptacle portion having upright sidewalls,
  - 2. a cover fitting over said receptacle portion and having sidewalls extending downwardly along the sidewalls of the receptacle portion, and
  - 3. one of the sidewalls of said cover having a cutout portion providing a window, and
- B. a card having a fold and separating line extending thereacross dividing said card into an article display panel and a juxtaposed removable stock reorder panel,
  - 1. said article display panel of said card extending into the receptacle portion of said box, said articles being attached to said display panel for displaying said articles separate from said shipping box,
  - 2. the fold and separating line of said card extending along and over the top of one sidewall of said receptacle portion, and
  - 3. said stock reorder panel of said card extending downwardly from said fold and separating line between said one sidewall of the receptacle portion and the windowed sidewall of said cover and being exposed through said window.
